SHIP'S LIFESAVING DEVICE

Harry Barlow and Torger Birkland,
Port Blakely, Wash.

Application September 11, 1934, Serial No. 743,620

3 Claims. (Cl. 114—190)

This invention relates to a ship's life saving device, and in a specific sense, it relates to a life buoy thrower, also to an improved holder for an illuminating device which is attached to the life 5 buoy for marking its position when thrown into the water.

One object of this invention is to provide a very practical and effective device that will apply stored power for throwing life-rings or life 10 buoys off at a distance from the ship, so the person overboard, seeing the buoy or the light of the illuminator, will swim away from the ship, towards the buoy, and avoid the danger of being struck by the ship's propeller, as has happened 15 heretofore.

Another object is to provide improved means to hold the illuminator in such stable and protected position that it will not be detrimentally affected by the rolling of the ship nor by weather 20 conditions, but will operate unfailingly when put to use.

Another object is to provide a device of this kind with spring-tensioning means by which it can be made to throw the buoy to greater or less 25 distances; and with training or aiming means, under control of an operator, for enabling such operator to cause the buoy to be thrown to a point near the person overboard.

Other objects and important features are 30 pointed out and implied in the following details of description of the invention as exemplified in the several forms of the invention shown in the accompanying drawings wherein:

Fig. 1 is a top plan view of one form of the invention in its normal or set position and having 35 an annular life-buoy therein, but the illuminator or illuminating device and its cover being omitted.

Fig. 2 is a side elevation of a part of the device, and of a fragment of a ship to which it is attached, other parts being in vertical section.

Fig. 3 is a view showing most of the parts in vertical section along the line 3—3 of Fig. 1, the remainder being in elevation.

Fig. 3a is a detail view of releasing gear shown 45 in Fig. 3.

Fig. 4 is a side elevation showing a somewhat different form of spring device, while eliminating some features shown in Figs. 1, 2 and 3, also 50 showing a part of the buoy, its becket, its illuminator-attaching line, and its receptacle in broken lines at the left of the parts in full lines.

Fig. 5 is a view at right angles to Fig. 4, partly 55 in vertical section along its axial plane.

Fig. 6 is a side elevation showing another modi-

fied form of spring device and another form of detaining device or trigger mechanism, and showing the flexible stopping member suitably adjusted for causing the buoy to be thrown upward from its container, as the broken lines indicate. 5

Fig. 7 is an elevation taken at right angles to Fig. 6, also showing both the full-lines position and the broken-lines position of the buoy and the receptacle therefor. 10

Fig. 8 is a side elevation showing other modifications of certain parts of the invention, especially the straight-thrust buoy thrower.

Fig. 9 is an elevation taken at right angles to Fig. 8, or as viewed from the rear, the left end 15 of Fig. 8.

Fig. 10 is a top plan view of the form shown in Figs. 8 and 9.

Referring to these drawings by the reference numerals which refer to similar parts in the several views, the invention is described in detail 20 as follows:

In a broad sense, each form of the invention includes or comprises a receptacle for holding a life-buoy therein and free to be thrown therefrom by a quick movement and sudden stop, a spring device normally under tension and operable to effect said quick movement, a stop for terminating the quick movement, a support provided with means to secure it to a ship and having the spring device secured thereto, an illuminator provided with means to attach it to a buoy so it will go with the buoy when the latter is thrown from the carrier or receptacle, a lid for the illuminator secured to the support and normally covering the illuminator so as to protect it from weather and from untimely operation, and means to hold said illuminator normally 25 stable so it will not be detrimentally affected by rolling of the ship and will stay engaged with its lid until it is pulled therefrom by a person or by the buoy when thrown from the receptacle. 30

Fig. 1 is a top plan view of one form of the invention in its normal or set position and having an annular life-buoy therein, but the illuminator or illuminating device and its cover being omitted. 35

In Figs. 1, 2 and 3, the buoy is shown at 5; its becket, at 7; its holder or receptacle, at 32; its spring device, at 34, 38, 45, 62, the helical torsion-spring 38 having one end secured to the shaft or axle 34 (at 38b) and its other end secured to the hollow cylinder 62 (at 38a), the shaft or axle 34 being journaled in bearings of the member 45 which constitutes a part of the 40 upright support to be more fully described hereinafter. The illuminator 12 and its lid 12a are preferably united by a snug and substantially weatherproof joint that is not so tight as to prevent unfailing separation by pull of the thrown 45

50 buoy. The illuminator 12 and its lid 12a are preferably united by a snug and substantially weatherproof joint that is not so tight as to prevent unfailing separation by pull of the thrown 55

buoy without materially affecting the distance of throw of the buoy, the pull being effected through the flexible connection or line 13 which is secured to the becket and to the bottom of the illuminator which may be operated by acetylene therein which comes into contact with water when the buoy is thrown into the water, or may be of any appropriate type which becomes automatically operable upon removal of its lid, or upon removing it from its lid. A part of said upright support is shown at 31, an upward extension of the part 45, the lid being secured thereto by a link or connection 11, and the arms 30 of the member 31 embracing the lid and combining therewith and with the bottom-seats 30a (which project laterally or horizontally from the upright part of the supporting element 31) to support the illuminator and keep it stable.

The carrier or receptacle 32 is preferably formed of two U-shaped metal strips, as shown in Figs. 1, 2 and 3, viz., a vertical U-strip having its upper end united with the middle part of a horizontal U-strip so as to form a comparatively light and rigid crate-like hollow receptacle having narrowly spaced sides or walls which approximately touch the sides of the buoy held thereby in a vertical position and normally retain it in such position. The open end of the horizontal U-strip is secured to the upper side of the spring device, specifically, to the hollow cylinder 62. One end of this cylinder is journaled on a boss of the supporting member 45, and its other end is journaled on a hub of a worm-gear wheel 61 that is secured to the shaft 34 by any appropriate means. A worm 60 is in operative engagement with the worm-gear wheel for turning the latter so as to turn the axle 34 relative to the cylinder 62 and thereby increase or decrease the tension of the spring 38 while a pawl 35 (Figs. 1 and 3) extends through a slot 32x (Fig. 2) and serves as means to hold the receptacle against pressure of the spring 38 which continually tends to swing the receptacle and buoy about the axis of the spring device.

In addition to the parts of the upright support described in the foregoing, such support also includes a tubular shank or base 63 having its upper end welded to or otherwise united with the member 45, and this element 63 has a bearing collar 65 united therewith and resting on an annular bearing 64 that rests on and extends through the ship's deck 74 which is apertured to receive the lower end of the shank 63 which has a lever or arm 66 secured thereto for manually turning the shank and all that is supported thereby. A graduated disc 67 is secured to the under side of the deck and serves as a guide to the operator who manipulates the device from below the deck 74, turning the shank and its dependent adjuncts, by means of the lever 66, according to the direction the buoy is to be thrown, as indicated on the disc or dial 67. A set-screw 73 is operable to secure the lever 66 at any desired adjustment with respect to the dial 67.

A tubular axle 68 extends through the shank 63 and is rotatable therein by means of arms 68a and 68b which are secured to its lower end. A lever 69 is pivoted on the arm 68a and is slidably engaged with the arm 68b, so it may be used in combination with these arms for turning the tubular shaft 68 on which the worm 60 is secured, so this turning effects the turning of the members 61 and 34 for tensioning spring 38 or for decreasing its tension, according to the

direction of movement of the handle or lever 69. This handle also has another purpose, viz., lifting a wedge-rod 71 whose lower end may rest on the lever 69, although we have shown a pin or abutment 72 resting on the rod-lifting lever 69. The upper end of the rod 71 is diagonally slabbed as shown in Fig. 3a, and this slabbed side or cam-surface rests against the pawl or detent 35 while the latter engages the receptacle 32 for holding it in the set normal position.

The operation is as follows:

On hearing the cry "man overboard!", a member of the crew will rush to the ship's rail and locate the position of the man in the water, while another will rush to the life-saving device and be guided by a signal from the man at the rail, as to the direction and distance for throwing the buoy; then, very quickly adjusting the device by means of the levers 66 and 69 (while allowing for travel of the ship), the operator then lifts the handle 69, so the cam-end or wedge-end of the rod 71 pushes the pawl 35 out of engagement with the carrier or receptacle 32, and the spring-device now operates to turn the receptacle to its broken line position (Fig. 2), where its stop-lug 62a strikes the stop-lug 50; and now the buoy's momentum carries it from the receptacle in a trajectory and at a distance commensurate with the tension of the spring 38. The attaching line 13 (under impulse of the flying buoy) pulls the bottom of the illuminator off the seats 30a, the springy arms 30 yielding to permit such movement, so the members 12 and 12a first swing out in the direction of the trajectory, but as such movement of the lid 12a is limited by the link 11, the illuminator 12 leaves the cover or lid and follows the buoy for illuminating it and guiding the overboard person to the buoy.

It is obviously within the scope of this invention to extend the shaft 68 and rod 71 upward and to apply manipulating devices thereto so they can be manipulated either by a person on the deck 74 or by a person under the deck, so the invention is not limited to the location of the manipulating devices, nor to the exact form herein described.

In Figs. 4 and 5, the members 5, 7, 13, 11, 12a, 14, 30 and 31 are substantially the same as previously described; but the receptacle 32a and its axle 34a are of somewhat different form, the former being united with the axle instead of with the hollow cylinder 62 of Figs. 1, 2 and 3. In this modified form, the axle 34a is rotatable in a tubular bearing member or casing 39 by means of a helical torsional spring 38 which has one end connected to the shaft 34a while its other end is secured to the hollow cylinder or tube 39, but the latter is held fixed by means of U-bolt-clamps 40 on a post 41 of the ship's rail and on a bracket 45a which is secured to parts 42 and 43 of the ship's railing. One end of the tube 39 is also secured in a bearing on a bracket 45b on the ship-rail member 42. A slot 34b is provided in the inner end of the axle 34a and into this slot extends a tongue of the detent 35a whose purpose and function is the same as that of the pawl or detent 35 of Figs. 1, 2 and 3, viz., to hold the spring under tension so it cannot operate until released by disengagement of the detent from the unit that comprises the members 32 and 34a. The member 35a is longitudinally movable in the tube 39 which is slotted at 39a to receive a pin 36 which extends therethrough and through the detent 35a, so the latter can not turn. A helical compression spring 37 bears against the

pin 36 and against a bearing 39b in the end of the tube 39 so as to yieldingly hold the detent 35a in the slot 34b; a puller or line 46 is connected to the detent 35a and extends outward through 5 a guiding and protecting tube 47 which may be suitably curved to reach any point in the ship, for instance, the "look-out", tower or bridge, so the wire or line 46 can be pulled from that point for releasing the spring device and permitting it 10 to throw the buoy and the illuminator. In this form, the parts 41, 43, 44, 31, and 45a, either with or without the members 42 and 45b, constitute the upright support that corresponds to the parts 63, 45, and 31 of Figures 1, 2 and 3.

15 The stopping device for this form, may consist of a flexible cable or line 50a having one end secured to the receptacle while its other end is secured to an adjustably mounted member 50b that is clamped on the rail-member 44 by means 20 of a bolt and a wing nut. When the wing-nut is loosened, the member 50b can be slid along the rail member for obtaining the desired adjustment for obtaining the desired trajectory.

The distinctive features in Figs. 6 and 7 include 25 the receptacle 32b—38c, the part 38c being an extension of the spring device 38b which is a flat spiral spring and is united with the axle 34b, the latter being united with the support or upright 45c. The detent 48 is in the form of a 30 hook-lever, is pivoted in a bearing-bracket 48b which is secured on the rail-member 42, and is operated by its arm 48a that is attached to a puller or line 46 which extends to the desired manipulating point through a guiding tube 47.

35 The stopping device, in this form of the invention, consists of a flexible element 49 including several links which are interchangeably connectible to a pin or stop-member 50c. The trajectory may be increased or decreased according to the link connected to the member 50c.

The distinctive features of Figs. 8, 9, and 10 are explained as follows: Instead of the receptacle 32d being swung in an arc of a circle, as previously described, it is moved in a straight 45 horizontal line by means of its spring device 38d in a tubular casing 39d, and is supported thereby in combination with a guiding and controlling rod 50d. This rod extends through a tubular extension 32e of the receptacle, this extension being 50 slidable in the casing 39d by pressure of a helical compression spring 38d which bears against the tubular extension and against a bearing and closing cap of the casing 39d. A detent-lever 48d normally engages with a notch in 55 the rod 50d and holds the latter retracted against pressure of the spring 38d. The puller 46 engages with the detent-lever and passes thence through the guiding tube 47, for operation at a distance, as previously explained regarding other 60 forms of the invention.

A gate 53 is hinged to the outer end of the receptacle and has an arm pivoted at 54 to a link

55 which latter is pivoted to an actuation and holding lever 56, the latter being pivoted to an ear on the receptacle 32d, so when the receptacle is moved forward by its spring 38d, the parts 53, 54, 55 and 56 are carried therewith while a 5 stud on the lever 56 moves along a cam-track 57 and is thereby swung backwards, pulling the link 55 and thereby opening the gate, so that, when the receptacle is stopped by the stop member 52 striking the end of the tube 39d, the gate 10 is wide-open so the buoy 5 can pass therefrom without interruption, and will carry the illuminator therewith by means of the connecting line 15 13. The purpose of the gate 53 is to keep the buoy from rolling out in consequence of the 20 rolling of the ship, so there must be a securing means as well as the automatic opening means 54, 55, 56 and 57. To provide for automatic closing and holding of the gate, a cam-track 58 may be provided to engage with the lever 56 as 25 the receptacle is return to its set position, and to hold the gate closed until the receptacle is 30 moved forward for shooting out the buoy.

These several forms of the invention are merely 25 illustrative of a few of the many forms which may be made within the scope of the inventive ideas herein shown and described; so we do not limit our patent protection to these forms in a specific sense; but what we claim as our invention is:

1. In a ship's life-saving device, the combination 30 of a receptacle having spaced elements constructed and arranged in proper relation to loosely engage with widely spaced segmental parts of an annular life-buoy so as to support the latter in freely removable relation and in upright position, a spring device united with said receptacle, means normally holding the spring restrained and releaseable for effecting a quick movement of the receptacle in the proper direction for throwing the life-buoy edgewise from the ship into the water, and an upright support provided with means to secure it to the ship and with means to support the receptacle and the 35 spring device.

2. The combination defined by claim 1, means to limit the forward motion of the receptacle, means to adjust the limiting means so as to vary the trajectory of the buoy when it is thrown from the receptacle, and means to turn said upright support about a vertical axial line and thereby to vary the direction of throwing of the buoy by said receptacle.

3. The combination defined by claim 1, and means independent of the spring restraining 55 means to increase and decrease the effective power in said spring device so as to vary the force and speed of movement of the receptacle when throwing the buoy so as to throw the latter various distances.

HARRY BARLOW.
TORGÉR BIRKLAND.
